UNITED STATES PATENT OFFICE.

FRANCIS E. BRADY, JR., OF MUNCIE, INDIANA, ASSIGNOR OF ONE-THIRD TO ROY A. OPPENHEIM AND ONE-THIRD TO DAVID OPPENHEIM, BOTH OF DETROIT, MICHIGAN.

PUMP.

Application filed March 9, 1925. Serial No. 14,083.

This invention relates to rotary pumps and more particularly to that type of pump wherein the rotor or impeller is provided with teeth or projections forming pockets 5 therebetween lateral to a channel in which the main stream of water is carried through the pump by virtue of the shear resistance between such main stream of water and the water in the said pockets, the invention having for its object to provide an economical and efficient pump of this type wherein advantage is taken of the fluid cohesiveness, adhesiveness and shear resistance for the securing of a steady flow of water through 10 the pump and the obtaining of a very substantial capacity in the pump relative to the diameter of the rotor and in comparison to centrifugal pumps of equal diameter at a given number of revolutions per minute. 15 A further object is to provide a pump of such type having an annular or circular channel therein and slotted transversely of the said channel wherein the head resulting from the operation of the said pump increases in proportion to the square of the speed and to the diameter of the impeller and in proportion to the cube of the area of the slots in the said impeller.

A further object is to provide in such a pump for the adjustment of means interrupting the continuity of the circular or annular channel whereby the stream is diverted from the pump in such manner that the said means may be readily adjusted or reset in the said channel to compensate for wear or to secure the positioning of the said means to the greatest advantage; a still further object of the said invention being to provide in such a pump a channel converging towards the base thereof and interrupted by a correspondingly tapering partition whereby the spacing of the walls of the said partition from the walls of the said channel may be determined by the extent to which the said partition is entered into the said channel.

Still further objects subsidiary to or resulting from the aforesaid objects, or from the construction or operation of the invention as it may be carried into effect, will become apparent as the said invention is hereinafter further disclosed.

In carrying the said invention into effect, I may provide within a suitable casing provided with an inlet and an outlet, a rotor in

the form of a disk, radially or transversely slotted to provide teeth thereon and incidently with pockets between the said teeth, said disk having a continuous groove turned therein and passing through the said teeth, the lateral walls of which groove converge 60 towards the bottom thereof, and a partition member extending inwardly of the casing into the said groove adjacent the outlet opening and conforming in cross sectional configuration with the cross sectional shape of 65 the said groove whereby the said partition may be adjusted in its relationship to the bottom and side walls of the said groove by increasing or decreasing the extent to which the said partition enters the said groove. 70

All of which is more particularly described and ascertained hereinafter, by way of example, having reference to the accompanying drawings, wherein

Figure 1 is a fragmentary elevation with 75 the cover plate partly broken away of a pump embodying the said invention;

Figure 2 is a fragmentary plan of the same;

Figure 3 is a sectional elevation of the 80 same taken on the line 3^x—3^x, Figure 1;

Figure 4 is an elevation partly in section of a modified form of the device;

Figure 5 is a plan of the same;

Figure 6 is a transverse section taken on 85 the line 6^x—6^x, Figure 4;

Figure 7 is an elevation shown partly broken away and in section of a further modified form of the pump;

Figure 8 is a plan of the same; and 90

Figure 9 is a transverse section of the same partly shown in side elevation.

Similar characters of reference indicate similar parts in the several figures of the drawings.

In Figures 1, 2 and 3 the rotor 1 is shown as mounted in a casing 2, and on a driving shaft 3 extending through the said casing, which casing is provided with a cover plate 4 and has inlet and outlet passages 5 and 6 100 respectively. The rotor 1 is in the form of a disk or drum, the face of which is provided with a circular groove or channel 7 flanked by inner and outer rows of teeth 8 and 9 on opposite sides of the said groove or 105 channel, which teeth are formed by the radial slotting of the face of the rotor, the slots forming pockets 10 and 11 between the

said teeth, and it will be noted that the lateral walls of the said channel converge towards the base thereof so that the channel is substantially narrower at the said base than at the top.

The purpose of the said channel, teeth and intermediate pockets is to produce a flow of fluid through the pump from the inlet to the outlet passage thereof upon the rotation of the said rotor, this flow being induced by the shear resistance between the fluid in the pockets between the teeth of the rotor and the main body of fluid in the channel 7 which is also a result of the cohesive nature of the fluid, the action still further being assisted by the adhesive nature of the fluid so that motion is transmitted thereto by the side walls and base of the channel 7.

This utilization of the shear resistance and cohesiveness of a fluid is very effective in impelling fluid through a pump such as that illustrated, and in order to effect the direction of water into the channel from the inlet passage 5 and from the channel through the outlet passage 6, a partition member 12 is provided (in this case integral with the cover plate 4) which extends into the channel 7 and interrupts its continuity so that it prevents fluid being drawn from the passage 6 by the action of the rotor and ensures the interruption of the flow of fluid around the pump casing whereby it is forced out therefrom through the said passage 6. For this purpose the partition member must be more or less fit and conform to the shape of the passage 7, wherefore member 12 is provided with beveled faces 13 and 14 and an end face 15 conforming to the converging walls of the channel 7 and the flat base respectively of the said channel.

To permit adjustment of the partition member so that it may be correctly positioned in the channel 7 to avoid unnecessary frictional contact with the teeth 10 or 11 or the bottom of the channel, and also to permit of its readjustment to suit different conditions of operation or to compensate for wear of the walls of the groove or of the partition member, this member is capable of variation as to the extent to which it may enter the said channel. In this example such adjustment may be effected by regulating the position of the rotor such as by the insertion of a plate or shim 18 between the rotor and the casing 2 of the pump.

It will be understood however, that the face of the rotor, the casing or the cover plate, or of any or all of these, may be machined to permit the entrance of the partition member into the channel to the desired extent to compensate for any wear which may have taken place disturbing the relationship between the said partition member and the channel.

In Figures 4, 5 and 6 a somewhat different

cover plate 16 is shown wherein the inlet passage 17 passes beyond the partition member 18 so that the fluid flows in a more or less continuous direction from the said inlet passage to the channel 7 of the pump instead of being reversed in its direction as indicated by the arrow in Figure 2 of the drawings, and the outlet passage 19 forms practically a continuation of the said channel 7 so that fluid is delivered therefrom without great variation of direction, it being understood that the inlet and outlet passages may be arranged in any convenient form or position relative to the partition member which may be thought necessary or desirable.

Figures 7, 8 and 9 illustrate a form of pump wherein the rotor 20 is in the form of a disk or drum, the peripheral portion of which is provided with an annular groove or channel 21 flanked by flanges which are transversely slotted to provide teeth 22 and 23 on opposite sides of the said groove or channel, the slots forming pockets 24 and 25 between the said teeth and the lateral walls of the said channel converging towards the base thereof as and for the purposes already explained.

In this example the casing 26 is provided with inlet and outlet passages 27 and 28 between which is located a boss or enlargement 29 on the said casing, the said boss being bored to accommodate the stem 30 of a partition member 31 projecting into the said channel 21 and operating to direct the flow of fluid into and from the channel 21 as described with reference to the partition member illustrated in Figures 1 to 6. The said partition member 31 is also provided with beveled lateral faces 32 and 33 and an arcuate end face 34 conforming respectively to the converging walls of the channel 21 and the curved form of the base of the said channel; and the stem of the said partition member is slidable in the bore of the boss 29 which is provided with set screws 35 by means of which the said partition member may be secured in any position of adjustment to suit conditions of operation or to compensate for wear.

36 is a cap threaded onto the outer end of the boss 29 and enclosing a leak-proof washer 37 to prevent escape from the casing of any fluid which may pass upwardly around the stem of the partition member.

As will be apparent from an examination of Figures 1 and 2, the inner end of the partition member may be expanded to provide inclined guiding walls 38 and 39 extending to assist the direction of fluid into and out of the channel of the rotor.

A very marked efficiency has been obtained with pumps of this type as compared with the ordinary centrifugal pump, and in actual practice using a pump constructed in accordance with Figures 7, 8 and 9 of the

drawings appended hereto, this has been borne out in a marked manner.

It will be apparent that in addition to the efficiency of the operation of the device it is readily adaptable to fine adjustment and resetting of the parts so that they may be easily maintained in their most efficient co-operating relation, and the device furthermore admits of great simplicity of manufacture, assembling and replacement of parts, at the same time being very unlikely to get out of order, except under the most adverse operating conditions.

This invention may be developed within the scope of the following claims without departing from the essential features of the said invention, and it is desired that the specification and drawings be read as merely illustrative and not in a limiting sense, except as necessitated by the prior art.

What I claim is:—

1. In a rotary pump, a rotor having a marginal channel, teeth on opposite sides of said channel forming pocketed walls thereof, an enclosure for said rotor having inlet and outlet orifices communicating with said channel, and a partition member adjustably entering said channel beyond said outlet orifice to divert fluid from said channel into said outlet orifice.

2. A device according to claim 1 wherein the lateral walls of said channel converge towards the base thereof and the partition member is beveled to conform to the shape of the said channel.

3. In a device of the class described, a channeled rotor, an enclosure having inlet and outlet orifices communicating with said channel, a partition member located in said channel intermediate said openings, and means adjustably determining the extent to

which said partition member enters said channel.

4. A device according to claim 3 wherein the walls of the channel converge towards the base thereof and the partition member is correspondingly beveled, and means adjustably determining the clearance between said partition member and the side walls and base of said channel.

5. In a rotary pump, a disk-like circular channel forming one face thereof, the walls of said channel converging towards the base thereof and being slotted to form teeth, an enclosure for said rotor having inlet and outlet orifices communicating with said channel and a beveled partition member extending inwardly of said closure intermediate said inlet and outlet orifices and conforming to the shape of said channel, and means adjusting the respective positioning of said rotor and the partition carrying wall of said closure whereby the extent of the entrance of said partition into said channel may be regulated.

6. In a rotary pump having a channeled impeller wherein the flow of fluid is induced in said channel by the rotation of said impeller, means projecting into said channel and deflecting fluid therefrom, said means being adjustable as to clearance therebetween and the walls and base of the channel.

7. In a rotary pump, a rotor having a continuous fluid conveying channel therein, the walls of which are tapered towards the base of said channel, a correspondingly beveled partition member interrupting said channel, and adjustable means whereby the position of said member relative to the confines of said channel may be varied.

In testimony whereof I affix my signature.

FRANCIS E. BRADY, JR.
